COMBINED CONFECTIONERY KETTLE AND CONTROL PANEL

Thedosius N. Peterson, 201 Mount Lebanon Road,
Wilmington, Del. 19803

Filed Nov. 18, 1965, Ser. No. 88,145

Term of patent 14 years

(Cl. D55—1)

FIGURE 1 is a right front perspective view of the range embodying my new design; and

FIGURE 2 is a left front perspective view thereof.

The rear of the control panel and support is plain.

I claim:

The ornamental design for a combined confectionery kettle and control panel, as shown and described.
